TANK TRAILER

Charles E. Mendez, Tampa, Fla., assignor to Redwing
Carriers, Inc., Tampa, Fla., a corporation of Florida

Filed May 4, 1964, Ser. No. 79,799

Term of patent 14 years

(Cl. D14—3)

FIGURE 1 is a side elevational view of a tank trailer embodying my new design and the opposite side of the tank trailer is similar to that shown in this figure with the exception that a ladder extends from the top of the trailer and downwardly along the side of the trailer;

The dominant features of my design reside in the portions shown in full lines.

I claim:

The ornamental design for a tank trailer, substantially as shown and described.
